UNITED STATES PATENT OFFICE.

WILLIAM E. GREENAWALT, OF DENVER, COLORADO.

APPARATUS FOR THE EXTRACTION OF METALS FROM THEIR ORES.

No. 901,611.

Specification of Letters Patent.

Patented Oct. 20, 1908.

Application filed February 1, 1904, Serial No. 191,600. Renewed March 30, 1908. Serial No. 424,117.

To all whom it may concern:

Be it known that I, WILLIAM E. GREENAWALT, a citizen of the United States, residing at Denver, in the county of Denver and State of Colorado, have invented certain new and useful Improvements in Apparatus for the Extraction of Metals from Their Ores, of which the following is a specification.

My invention relates to improvements in apparatus for the extraction of metals from their ores by the use of chlorin.

It is intended more particularly as an apparatus well designed to carry out my processes as described in my applications for process patents, Serial Number 47,975, filed February 19, 1901; Serial Number 127,290, filed October 14, 1902; and Serial Number 144,363, filed February 21, 1903; although I do not wish to limit its use to these processes alone.

The process, briefly described, consists in absorbing chlorin in aqueous solution under varying degrees of pressure whereby, according to Henry's law, a solution of chlorin is obtained corresponding to the chlorin pressure used.

Henry's law states that "the volume of the gas absorbed by a liquid is directly proportional to the pressure of the gas." If the pressure be doubled the same volume of liquid will dissolve twice the volume of the gas. Thus, if 100 volumes of water at 10° centigrade dissolve two volumes of chlorin under the standard atmospheric pressure, under twice the pressure (two atmospheres) the same volume of water will absorb twice the volume of chlorin, or four volumes. The solubility of chlorin in water under ordinary conditions is small. At or about 10° water will absorb about $2\frac{1}{2}$ times its volume of the gas. In practice it will usually be less. Water, to the extent of half the weight of the ore is ordinarily put into a chlorination barrel with the ore to make an easy flowing pulp. This amount of water, per ton of ore, can, under ordinary conditions, dissolve about 40 ounces of chlorin. Usually from 50 to 80 ounces are required. It will be seen from Henry's law just stated, that by doubling the pressure of the gas to about two atmospheres or about 15 pounds per square inch, that the fifty to eighty ounces required can readily be brought into solution. A pressure of 5 to 25 pounds per square inch ought to treat the most refractory ore. It will be seen that this is a simple matter as

compared with making and applying liquid chlorin which requires low temperatures and high pressure to liquefy it. Besides my method of applying the chlorin has marked improvements over methods of applying chlorin or chlorin generating compounds directly to the ore in the barrel as will appear later on in the specification.

The primary object of this process and apparatus is to apply chlorin, as generated by electrolysis, to the reduction of gold ores without resorting to high pressures or low temperatures or without first combining the chlorin with an accessory compound, such as calcium hydrate to form bleaching powder.

An essential feature of both my process and apparatus consists in first absorbing the chlorin in the amount of water required to make an easy flowing pulp with the ore, outside of the chlorinating vessel, and then introducing the solution and the ore into the vessel to be treated. With the small pressures used, there will be no mechanical difficulties in the manipulation.

The accompanying drawing illustrates my apparatus in detail for carrying out the process.

1 is an electrolytic cell for generating chlorin from sodium chlorid.

2 is a compressor which exhausts the chlorin from the positive compartment of the electrolytic cell and forces it under suitable pressure into the closed absorption chamber.

4. When no pressure is necessary, by the proper adjustment of the valves, the chlorin is passed by the compressor directly into the absorption chamber. When only a small pressure is needed it can be best obtained by working the positive compartment of the cell under pressure. This can do no harm. Indeed, it may be decidedly beneficial, in that it increases the pressure from the positive to the negative compartments and thus prevents the formation of hypochlorites by the mingling of the chlorin and caustic soda through the diaphragm. In some cells this difficulty is minimized by keeping the caustic soda in the negative compartment at a lower level than the brine in the positive compartment; in others, where the cathode is in intimate contact with the diaphragm, the negative compartment is vacant. The object in either case is the same, namely, to prevent the caustic soda from working back into the chlorin compartment by causing a flow in the

opposite direction, due to unequal pressures in the compartments. The same results can be attained by working the positive compartment under pressure of the liberated 5 chlorin gas, even if the liquid in the negative compartment is at the same or higher level than the brine in the positive compartment.

In order to properly absorb the chlorin in water the chamber 4 is made with shelves 10 which project alternately from top to bottom. These shelves can be made of various materials, such as lead or cement but they are best made of large sheets of plate glass. The idea of these shelves is to subdivide the 15 water and increase its surface by spreading it out in thin sheets and letting it flow from one shelf to the other whereby most favorable conditions are attained for quickly and thoroughly dissolving the chlorin.

20 In order to spread the water satisfactorily at its introduction into the chamber, nozzles 6 are so arranged as to introduce it into the upper compartment of the chamber in a fine spray. The spray also offers the greatest 25 possible surface to the chlorin. The water after it passes from one shelf to the other in an atmosphere of chlorin issues from the chamber through the pipe 7 into the closed storage tank 8, where it is at all times ready 30 for use.

10 is a chlorinating barrel into which the ore is placed for treatment with the chlorin solution.

It is evident that when a super saturated 35 solution of chlorin is introduced into the barrel, unless the necessary precautions are taken, the pressure will be momentarily released and much of the chlorin will no longer be held in solution but will diffuse in the 40 barrel as free gas. It would not be long however before the gas in the barrel would acquire the same tension as the gas in the solution. There is no particular harm in this, for as the chlorin in solution in the 45 barrel is consumed more would be taken into solution.

If it should be desirable to introduce the supersaturated solution without the diffusion of free gas in the barrel, it can readily be 50 done by first connecting the gas supply of the absorption chamber with the barrel by means of a pipe or conduit 3^b. Chlorin will then flow into the barrel until equilibrium is established in the gas pressure. The solution 55 can then be introduced into the barrel through the pipe or conduit 9 under the same pressure as it is in the absorption chamber. Then all the chlorin which is in solution will remain in solution while it is being introduced into the barrel and while the ore is being 60 treated. A simple modification of this method of procedure would be to first absorb the chlorin under ordinary atmospheric conditions, in the amount of water required to 65 make an easy flowing pulp and introduce the

solution and the ore into the barrel. Gaseous chlorin under any desired pressure could then be forced in to furnish an excess which would be absorbed by the water as rapidly as the chlorin in solution is consumed by the ore. 70 By this method it would not be necessary in many instances to absorb the chlorin in the absorption chamber under pressure. An ordinary solution might frequently suffice.

12 is a tank in which the desired metals are 75 precipitated out of the solution after treatment in the barrel.

13 is a filter press where the precipitated metals are caught and 14 a pump for returning the solution for resaturation and regeneration and re-use. This is desirable only when there is silver or copper in the ore worth recovering, or when some other chemicals are 80 in the solution which it is not desirable to lose.

To operate the process and apparatus, a saturated solution of salt is allowed to flow into the positive compartment of the electrolytic cell 1. An electric current is then passed from the anode to the cathode which 90 decomposes the salt. Chlorin is liberated in the positive compartment while caustic soda and hydrogen appear in the negative compartment. If the ore requires simply an ordinary solution of chlorin, it is passed directly 95 from the cell to the absorption chamber 4. If only a small pressure is needed, which will frequently suffice, the positive compartment of the cell is preferably worked under the pressure required. Should the ore require 100 a strong solution, it is preferably passed through the compressor 2 and forced into the absorption chamber under any pressure desired. In this way the pressure can be varied from zero upward, and the solution 105 can be varied from the ordinary solution, to one containing one or two per cent, and more of chlorin, and can be made to suit the varying ores. The water is introduced into the absorption chamber through the inlet 110 pipe 5 under pressure at least slightly in excess of the highest chlorin pressure likely to be used. As it flows over the shelves in thin sheets in an atmosphere of chlorin a solution of chlorin is obtained corresponding to the 115 chlorin pressure used. From 4 the chlorin solution flows through pipe 7 into the storage tank 8, from whence it is drawn into the barrel 120 as desired.

In charging the barrel, the required 125 amount of ore is first placed therein. Valves 12^a, or 11 are then opened to permit the escape of air as the solution forces its way down through the ore. This percolation may be facilitated by connecting the barrel 130 to an exhaust pump, but this will not ordinarily be necessary. Valve 3^c is then opened and chlorin allowed to flow into the barrel until equilibrium in the chlorin pressure is established between the barrel and the ab- 135

sorption chamber. Valve 9^a is then opened and the required amount of solution flowed in. Under these conditions there will be no tendency for the chlorin in solution to diffuse as free gas. At the same time there will always be a certain excess of chlorin which will be brought into solution as fast as the chlorin in solution is consumed. All the valves are then closed, the conduits or pipes disconnected and the barrel revolved from three to four hours. The solution is then filtered from the ore and flowed into tank 12 where the metals are precipitated. After settling, the solution is passed through the filter press 13 and there wasted or returned for resaturation and regeneration and re-use.

When water and liquid chlorin or water and a chlorin generating compound are put into a barrel, the chlorin is immediately converted into the gas and instantly rises to the surface of the charge of ore and water. Only a small portion, therefore, of the chlorin is retained in solution and is at once available for attacking the gold in the submerged ore. It is not until the water becomes thoroughly saturated that the full strength of the charge becomes available, and the conditions for the absorption of the chlorin in the barrel are about as unfavorable as they could well be. The chlorin has to be absorbed from above downward into a solid body of ore and water. These certainly are adverse conditions. Considerable time is therefore lost before most of the chlorin becomes effective.

In my process the chlorin which is dissolved in the water to any extent desired, outside of the barrel, under advantageous conditions immediately asserts its full strength on the ore as soon as it is charged into the barrel.

Having thus described my invention what I claim is:

1. In an apparatus for the hydrometallurgical extraction of metals from their ores the combination of an electrolytic cell for generating chlorin; a chamber in which the chlorin so generated is absorbed in aqueous solution; means of forcing chlorin gas into said chamber under pressure greater than atmospheric pressure, and a chlorinating vessel, separate and distinct from the absorption chamber, in which the ore is treated with the solution so formed.

2. In an apparatus for the hydrometallurgical extraction of metals from their ores the combination of an electrolytic cell for generating chlorin; a chamber having means of absorbing the chlorin by subdivision; means of forcing chlorin gas into said chamber under pressure greater than atmospheric pressure and a chlorinating vessel for treating the ore with the solution so formed.

3. In an apparatus for the hydrometallurgical extraction of metals from their ores the combination of an electrolytic cell for gen-

erating chlorin; a chamber in which the chlorin so generated is absorbed in aqueous solution; means of forcing chlorin gas into said chamber under pressure greater than atmospheric pressure; a chlorinating vessel, 70 separate and distinct from the absorption chamber, for treating the ore with the solution so formed, and means of establishing equilibrium in the pressure of the chlorin while the solution is being introduced into 75 the chlorinating vessel.

4. In an apparatus for the hydrometallurgical extraction of metals from their ores, the combination of an electrolytic cell for generating chlorin; a chamber having means of 80 absorbing the chlorin by subdivision; means of exhausting the chlorin from the electrolytic cell and forcing it into said chamber under pressure greater than atmospheric pressure, and a chlorinating vessel for treating 85 the ore with the solution so formed.

5. In an apparatus for the hydrometallurgical extraction of metals from their ores the combination of an electrolytic cell for the purpose of generating chlorin; a chamber in 90 which the chlorin so generated is absorbed in aqueous solution; a chlorinating vessel for treating the ore with the solution so formed; means of introducing the solution into the chlorinating vessel and means of supplying 95 an excess of chlorin under pressure in its gaseous form to the chlorinating vessel.

6. In an apparatus for the hydrometallurgical extraction of metals from their ores an electrolytic cell for generating chlorin; a 100 chamber in which the chlorin so generated is absorbed in aqueous solution; a chlorinating vessel for treating the ore with the solution so formed; a conduit for introducing the chlorin solution into the chlorinating vessel 105 and another separate conduit connecting the chlorinating vessel with a supply of gaseous chlorin.

7. In an apparatus for the hydrometallurgical extraction of metals from their ores the 110 combination of means of generating chlorin; a chamber in which the chlorin so generated is absorbed in aqueous solution; means of forcing chlorin into said chamber under pressure greater than atmospheric pressure, and 115 a chlorinating vessel, separate and distinct from the absorption chamber, in which the ore is treated with the solution so formed.

8. In an apparatus for the hydrometallurgical extraction of metals from their ores, the 120 combination of an electrolytic cell for generating chlorin; a chamber separate and distinct from the electrolytic cell, but communicating with the positive compartment thereof, in which the chlorin so generated is 125 absorbed in aqueous solution; means of exhausting the chlorin from the electrolytic cell and forcing it into said chamber; and a chlorinating vessel in which the ore is treated with the solution so formed.

9. In an apparatus for the hydrometallurgical extraction of metals from their ores the combination of an electrolytic cell for generating chlorin; a chamber, separate and distinct from the electrolytic cell but communicating with the positive compartment thereof, in which the chlorin so generated is absorbed in aqueous solution; means in said chamber of subdividing the solution where-
5 by a larger surface is exposed to the chlorin gas; means of forcing chlorin gas into said chamber under pressure greater than atmos-
pheric pressure; a chlorinating vessel in
10 which the ore is treated with the solution so formed; means of introducing the solution into the chlorinating vessel, and means of filtering the solution from the treated ore.
15 10. In an apparatus for the hydrometallurgical extraction of metals from their ores

the combination of an electrolytic cell for generating chlorin; a chamber, separate and distinct from the electrolytic cell but communicating with the positive compartment thereof, in which the chlorin so generated is absorbed in aqueous solution; means in said chamber of subdividing the solution where-
20 by a larger surface is exposed to the chlorin gas; means of forcing chlorin gas into said chamber under pressure greater than atmos-
pheric pressure; a chlorinating vessel in
25 which the ore is treated with the solution so formed; means of filtering the solution from the treated ore and means of returning the solution for regeneration and re-use.
